UNITED STATES PATENT OFFICE.

RICHARD WHITAKER, OF NEW BRUNSWICK, NEW JERSEY, ASSIGNOR OF
TWO-THIRDS TO ROBERT W. JOHNSON AND JAMES W. JOHNSON, OF
NEW BRUNSWICK, NEW JERSEY.

GAS-PUMP.

SPECIFICATION forming part of Letters Patent No. 742,940, dated November 3, 1903.

Application filed October 14, 1902. Serial No. 127,230. (No model.)

To all whom it may concern:

Be it known that I, RICHARD WHITAKER, a citizen of the United States, residing at New Brunswick, in the county of Middlesex and State of New Jersey, have invented certain new and useful Improvements in Gas-Pumps, of which the following is a specification.

This invention relates to air or gas pumps and valves thereof operating on a suitable fluid, the object of which is to provide means for reducing the area on the back of the discharge-valve which can be acted on by the discharge-pressure, the invention being shown in the accompanying drawing, which represents a vertical central section through the valves of a portion of a pump constructed in accordance with my invention.

In said drawing, A represents the valve-cylinder, which has in its interior a valve-seat, which consists, preferably, of a steel ring 2 to obtain a smooth and hard surface. Said ring rests upon an annular shoulder 3, formed in the interior of the cylinder above the piston-chamber 4. The valve-cylinder is bored 25 above the ring 2 to fit the periphery of the lower portion of the discharge-valve C; but the upper portion of the interior of the cylinder is formed by the pendent cylindrical flange of the cover B and is of smaller diameter to fit the periphery of the upper portion of the valve C, the bottom of said flange forming an annular shoulder 8, there being also an annular shoulder 5 around said valve between its upper and lower portions. This 35 annular shoulder 5 represents the difference in area between the upper and lower surfaces of the valve C exposed to discharge-pressure, and the pressure of the gas upon the shoulder 5 helps the spring R, so that a spring of less 40 power can be used to keep the valve C closed, while said pressure on the shoulder 5 is removed by suction through the pipe 12 at the time the piston Q ascends, and the pressure of said piston upon the gas above it slightly 45 lifts and opens the valve C. The head B of the cylinder is suitably attached to the body of the pump and has a pendent cylindrical flange that fits also the periphery of the upper portion of the valve C. Around the periphery of the upper portion of said valve

there are packing-rings 6 and around its lower portion are packing-rings 7 of suitable construction.

Within the wall of the cylinder A about half-way of the length of the discharge-valve 55 C there is an annular suction-chamber K, which is protected from the discharge-pressure on both its top and bottom by the packing-rings 6 and 7; but discharge-pressure is admitted on top of the valve C through a 60 passage S, formed in the body of the valve C, from the bottom discharge-chamber L of the pump-cylinder.

Within the hollow of the valve C is placed a coiled spring R of predetermined strength 65 according to the pressure intended to be exerted. One end of said spring bearing against the under side of the head B of the cylinder and the other end upon the bottom portion of the discharge-valve C acts to seat said 70 valve against the discharge-pressure acting on the under side of said valve.

Within the lower portion of the cylinder A is placed the piston Q. The chamber 4 below the piston is used as a receiver for the 75 sucked-in fluid, (which may be air, gas, or liquid.) This chamber 4 is in communication with the suction-chamber K by means of the pipe 12 alongside of the cylinder. The piston Q is hollow, and its top is provided with 80 a valve-seat q, upon which is seated the conical suction-valve D. Said valve has a stem E, which is received in and guided by a spider-boss Q², forming a part of the piston Q. Upon the stem E is mounted a broad head e, 85 fastened to the stem by nuts e². A coiled spring H is placed between the boss Q² and the head e to cause the suction-valve D to remain normally upon its seat q. The fluid passes from the lower chamber 4 under the 90 piston, through the opening shown closed by the valve D, into the chamber above said valve when the latter is opened. When the fluid is compressed by the piston Q, the discharge-valve C is raised and lets the fluid directly into 95 the chamber L and out through the pipe M.

The function of the chamber K is to supply suction fluid-pressure onto the small annular shoulder 5 of the discharge-valve. This shoulder is protected from the heavier dis- 100

charge-pressure by means of the packing-rings 6. The passage S, or a series of them, admits the discharge-pressure to the entire back of the discharge-valve, except the small area of 5 the shoulder 5, which has upon it the suction-pressure only. Consequently when the valve C is standing open the entire bottom of said valve is exposed to the discharge-pressure acting upward and a portion of the top of the 10 valve is exposed to the discharge-pressure acting downward and the area of the shoulder 5 is exposed to suction-pressure acting downward. The suction-pressure being much less than the discharge-pressure, the valve is 15 supplied with the pressure of the spring R, which is enough to seat the valve. The pressure against which the valve C will close is regulated by the predetermined strength of 20 the spring R or by the amount of the width or area of the annular shoulder 5, or by both 25 of said means together, thus limiting the pressure to which the pump can force a fluid into a receiver.

Having now fully described my invention, 25 I claim—

1. The combination of a valve-cylinder having in its interior an annular shoulder 8 dividing it into two chambers of different diameters, and having an annular chamber K in 30 communication with said shoulder, and a discharge-chamber on a lower level, a valve-seat alongside of the discharge-chamber, a spring having its upper end bearing against the under side of the top of the valve-cylinder and 35 its lower end pressing upon the top of the discharge-valve, and under said discharge-valve

a cylinder forming a chamber 4, a piston, and a spring-valve seated within said piston, substantially as described.

2. The combination of a valve-cylinder having in its interior an annular seat for a discharge-valve, said discharge-valve having a shoulder around its periphery, a chamber K within the walls of the cylinder and in communication with said shoulder, a discharge-chamber encircling the bottom of the discharge-valve and under said discharge-valve a cylinder forming a chamber 4, and within said chamber a piston having a spring-valve seated therein, and a pipe connecting the chamber under the piston with the chamber K, substantially as described. 40 45

3. The combination of a valve-cylinder having an annular chamber K and also a discharge-chamber in its walls, a discharge-valve having an annular shoulder in communication with the chamber K, the bottom of the discharge-valve being adapted while lifted to be in communication with the discharge-chamber, a cylinder forming a chamber 4, a piston under the discharge-valve, a spring-valve seated within said piston and a passage from under the piston to the chamber surrounding the shoulder on the discharge-valve, substantially as described. 50 55 60 65

In testimony whereof I affix my signature in presence of two witnesses.

RICHARD WHITAKER.
